COMBINED LINT REMOVER AND CASE

Vivian F. Robertson, Miami, Fla.

Application March 19, 1956, Serial No. 40,673

Term of patent 14 years

(Cl. D9—2)

FIG. 1

FIG. 2

Figure 1 is a front perspective view of a combined lint remover and case embodying my new design; and

Figure 2 is a front perspective view thereof in opened position with the removable lint remover in the case.

I claim:

The ornamental design for a combined lint remover and case, as shown.
